[57] CLAIM

The ornamental design for a pendant, substantially as shown.

DESCRIPTION

FIG. 1 is a front elevational view of a pendant showing my new design.

FIG. 2 is a rear elevational view of the pendant.

FIG. 3 is a side elevational view of the pendant, the opposite side being a mirror image thereof.

FIG. 4 is a bottom end view of the pendant.

FIG. 5 is a top end view of the pendant.
